Specification for Design.

Patented Oct. 11, 1921.

Application filed April 20, 1921. Serial No. 463,086. Term of patent 7 years.

To all whom it may concern:

Be it known that I, JOHN W. CARLSON, a subject of the King of Sweden, having declared my intention to become a citizen of the United States, residing at Chicago, in the county of Cook and State of Illinois, have invented a new, original, and ornamental Design for a Toy, of which the following is a specification, reference being had to the accompanying drawing, forming part thereof.

The figure is a perspective view of a toy showing my new design.

I claim:

The ornamental design for a toy as shown.
JOHN W. CARLSON.
